UNITED STATES PATENT OFFICE.

MAX FREUND, OF NEW YORK, N. Y.

BILL-FOLD.

1,310,010.

Specification of Letters Patent. Patented July 15, 1919.

Application filed March 27, 1919. Serial No. 285,513.

To all whom it may concern:

Be it known that I, MAX FREUND, a citizen of the United States, and a resident of the city, county, and State of New York, have invented a certain new and useful Improvement in Bill-Folds, of which the following is a specification.

This invention relates to a bill fold or pocket-book, and the object of this invention is to provide an article of this character which will be adapted to fold compactly into the smallest possible space, and yet afford the maximum amount of space or capacity for holding bills.

With these objects, and other objects which may hereinafter appear, in view, I have devised the particular arrangement of parts set forth in detail below, and more particularly pointed out in the claim appended hereto.

Reference is to be had to the accompanying drawing, forming a part hereof, in which,

Figure 1 is a front face view of my improved bill fold;

Fig. 2 is a front face view of the same in a partly folded position;

Fig. 3 is a front elevation of the bill fold in its completely folded position;

Fig. 4 is a sectional view on the line 4—4 of Fig. 3, looking in the direction of the arrows; and

Fig. 5 is a sectional view on the line 5—5 of Fig. 2, looking in the direction of the arrows, and showing one of the ways in which the bills may be carried.

Throughout the various views of the drawings, similar reference characters designate similar parts.

In the preferred embodiment of my invention, as disclosed in the accompanying drawing, 1 indicates the body portion of the bill fold which may be of leather, cloth or any desired material. The body portion 1 is in the form of a narrow elongated strip of material and at its upper longitudinal edge it is provided with a pair of integrally formed flaps 2 and 3. Connected to the lower longitudinal edge of the body of the bill fold is a flap 4, this flap being connected to the body portion by an expansible strip 5. The expansible strip 5 lies in between the body portion 1 and flap 4, and is secured thereto by the lines of stitching 6. On one

end of the body 1 of the bill fold is the closure flap 7, which is provided with closure means in the form of a snap-fastener member 8, which is adapted to engage a complementary snap fastener member 9 at the opposite end of the body portion 1, and on the rear face of the same, when the bill fold is in its completely folded position as shown in Fig. 3.

From the foregoing, the operation of my improved bill fold will be readily understood. To fold the device to its completely folded position as shown in Fig. 3, the bills 10, which are folded longitudinally, are placed upon the body portion 1, and the upper flaps 2 and 3 are then folded upon the dotted line 11, down upon them, after which the flap 4 is folded and rests upon or overlies the flaps 2. If desired, however, the flap 4 may be first folded over the bills, and then the flaps 2 and 3 folded to overlie the flap 4. The device in its partly folded position is shown in Fig. 2, after which it is folded transversely along the line 12, the body of the bill fold being cut away at 13 and 14, to readily permit folding of the device without causing undue bulkiness. After the device has been folded along the line 12, the closure flap 7 is caused to be folded to bring its fastener member 8 into engagement with the fastener member 9, and thus the device forms a small, compact article, which affords a large containing capacity. The expansible strip 5 allows a considerable degree of movement of the flap 4 away from the body portion 1, permitting the carrying of a considerable amount of bills, without in any way distorting the bill fold.

When desired, the flap 4 can be used to form a partition or dividing strip between the bills. This arrangement is disclosed in Fig. 5. The bills 10 may be bills of large denomination, and the bills 15 may be smaller bills, which can be readily kept separate from the bills 10 by placing the bills 15 in the position shown, wherein they are folded longitudinally similar to the bills 10, and the flap 4 is placed between the folds of the bills 15 as shown. By this arrangement, it is possible to remove any of the bills 15 without disturbing or disclosing the bills 10.

From the foregoing, it is obvious that my invention is not to be restricted to the exact

embodiment shown, but is broad enough to cover all structures coming within the scope of the annexed claims.

Having described my invention, what I claim is:

An article of the class described, comprising an elongated body portion, a pair of flaps formed integral on one of the longitudinal sides of said body portion, a cut-
10 away portion on the body portion inter-

mediate said flaps, a flap at the opposite longitudinal side of said body portion, an expandible strip connecting said flap and body portion, and a cut-away portion on said strip and flap, said flap and body portion 15 being adapted to be folded on a line connecting the two cut-away portions.

Signed at the city, county and State of New York, this 24th day of March, 1919.

MAX FREUND.
